PORTABLE MAGAZINE TYPE PACKAGE COOLER

Jean Robert Burdette, Lincoln, Nebr., assignor to
Carton Coolers, Inc., Lincoln, Nebr., a corpora-
tion of Nebraska

Application June 13, 1941, Serial No. 397,877

3 Claims.

(Cl. 312—36)

This invention relates to package cooling and dispensing equipment and has for its primary object, the provision of relatively small refrigerating apparatus for bottled goods, a portion of which remains on location at the point of purchase, while other parts thereof are interchangeable and movable to and from the source of bottle goods supply.

One of the important aims of this invention is the provision of a package cooler and dispenser having a removable container within which is disposed a bottle magazine and that is designed to be carried by specially formed means cooperable with certain parts of the container.

This invention has for a further aim the provision of a package cooler and dispensing unit, the inner portion of which may be quickly replaced and which has specially formed elements cooperable with an operating handle, permanently affixed to a displaceable cover of the unit.

One of the aims of the instant invention is the provision of bottle cooling and vending equipment, certain parts of which are removable as a unit, which unit comprises a container capable of holding a revolvable magazine and susceptible of collecting water produced by the melting of ice held within the magazine to cool the bottles while they are mounted in position for individual removal through a dispensing opening in a part of the case of the dispenser.

This invention contemplates providing bottle carrying means for a cooler and dispenser of the aforementioned character, which means may be stacked and transported to and from the bottling works while the outer case of the cooler is left intact at the point where sales are made.

The problems which the broad concepts of this invention solve are present when an attempt is made to transport the entire cooler and dispenser for the same is usually artistically finished and when marred or scratched becomes objectionable on location. The weight which the entire cooler presents is also prohibitive when an attempt is made to move the whole unit merely to refill the magazine thereof. The manner of handling the parts of a cooler and dispenser embodying this invention and further advantages arising from the unique assembly, will appear during the course of the following specification, referring to the accompanying drawings, wherein:

Fig. 1 is a top plan view of a cooler and dispenser made in accordance with the present invention, parts being broken away for clearness.

Fig. 2 is a vertical central sectional view through the same.

Fig. 3 is a top plan view of the container and parts associated therewith entirely removed from the case.

Fig. 4 is a side elevational view of the container illustrating the manner in which the sectional carrier is combinable therewith.

Fig. 5 is an enlarged sectional view through the carrier taken on line V—V of Fig. 3.

Fig. 6 is a plan view of the adaptor frame employed when stacking several containers; and

Fig. 7 is a side view of the adaptor frame in position between two containers.

The portable magazine type package cooler is relatively small and used at locations where a

small number of persons are to be serviced throughout the day. This type of package cooler and dispenser may be placed on location where the general public is not expected to operate the same but where a group of individuals are desirous of having available a cold bottle of beverage when the same is desired.

One of the shortcomings involved in servicing such relatively small equipment is the inconvenience to both the bottler and consumer, due to the bodily removal of the entire cooler from location when the same is to be refilled and reservised.

It is contemplated, therefore, that when this invention is followed, the insulated case 10 be left on location and only the hereinafter described

inner portions thereof replaced.

Case 10 has a displaceable cover 12 through which is formed a bottle dispensing opening that is confined beneath door 14, which in turn is released for movement to the open position only

after a coin has been inserted through slot 16 to operate mechanism within housing 18 and not here shown.

A conventional lock 20 secures cover 12 in the closed position and gasket 22 seals the joint be-

tween cover 12 and case 10.

An operating handle 24 secured to the outer end of shaft 26, which in turn is journaled in bearing 28 in cover 12, has a centering plate 30 secured to the inner end thereof, which plate has

inclined sides 32 terminating in horizontal out-

turned flange 34. A dog 36 pivotally mounted as

at 38 to shaft 26 is disposed for engagement with

one of a number of notches 40 formed in the

spider of magazine 42. This spider is divided to

present compartments 44 for bottles 46 and a

central opening in the spider receives a center

plate 30.

Magazine 42 is rotatably mounted through the

medium of pintle 48 that enters socket 50 created

in the lower wall or bottom of magazine 42. The

side walls of magazine 42 are of foraminous material in order that water may pass into container 52 when ice 54 contained in magazine 42 melts.

Turned flanges 56 on container 52 receive the ends of a specially formed carrier when the entire assembly within container 52 is lifted from case 10. The specially formed carrier, generally designated by the numeral 58, comprises sections 60 and 62 joined as at 64. Sections 60 and 62 combine to present a U-shaped body, the ends of the legs of which are out-turned to present ears 66 and 68 on sections 60 and 62 respectively.

When retaining ring 70 is moved to a position where it does not circumscribe a portion of sections 60 and 62, the sections may be moved about their pivotal connection 64 to allow ears 66 and 68 to be withdrawn from beneath flange 56.

The adapter frame illustrated in Figs. 6 and 7 is employed to stack containers 52 when they are transported in a truck or stored.

Obviously, if container 52 is made high enough to extend above the tops of bottles 46, such an adaptor frame is not necessary, but in the preferred embodiment of the invention, the relative heights of container 52 and magazine 42 is as shown in Fig. 2.

Elimination of weight and reduction in cost of manufacture are factors to be considered in constructing container 52.

Adaptor frame 74 is made in the form of an open, polygonal body conforming in shape to the flanged top of container 52. Upper and lower flanges 76 of frame 74 engage the top and bottom of the stacked containers, as the case may be, and corner members 78 embrace a portion of the vertical sides of containers 52 to preclude accidental lateral displacement. A strengthening brace plate 77 is spot-welded or otherwise secured to the bottom of upper flange 76 at each corner of frame 74 to add rigidity.

When dispensing and cooling structure is constructed as just described, the container 52, magazine 42, all bottles 46 contained therein, the ice 54 and such water as has collected in container 52, may all be quickly removed from case 10 and taken to a truck for transportation to the bottling works—there any objectionable washing, rinsing, dumping and other such work may be accomplished while a fresh filler of said enumerated parts is serving the owner of case 10 at the point where bottles 46 are dispensed.

The specially formed centering plate 30 cooperates with pintle 48 or any other similar bearing means supplied to rotatably mount magazine 42 so that merely closing cover 12 will dispose all of the parts in the operative position. When magazine 42 is centered, container 42 is spaced from the inner face of magazine 10. In other words, the cross sectional area of container 52 is slightly less than the cross sectional area of the inside of case 10 to present space 80 which cooperates with the insulated side walls of case 10 in preventing heat exchange.

Magazine 42 is free to rotate when the operator manipulates handle 24 but means is provided for arresting the movement of bottles 46 so that one is in register with the opening in cover 12 beneath door 14. Detents 82 pressed in the lower side of cover 12 receive the end of pin 84 which is pressed against the said underside of cover 12 by spring 86. This yieldable means of stopping bottles 46 as aforesaid, is mounted entirely upon cover 12 and therefore, magazine 42 is rendered rugged and without mechanism that could be injured during transportation to and from the point where it is to be introduced into case 10.

Having thus described the invention, what is claimed as new and desired to be secured by Letters Patent is:

1. In a package cooler and dispenser of the character described, an insulated case provided with a displaceable cover; a container removably fitted into said case; a pintle centrally located on the bottom of the container; a magazine for packages rotatably mounted on the pintle in the container; an annular member, having a series of notches and a central opening forming a part of the magazine; a shaft journaled in the cover; an operating handle on the shaft exteriorly of the case; a centering plate on the shaft formed to enter the central opening of the magazine; and a gravity actuated dog pivotally mounted on the shaft for entering one of the notches of the said member.
2. In a package cooler and dispenser of the character described, an insulated case provided with a displaceable cover; a container removably fitted into said case; a pintle centrally located on the bottom of the container; a magazine for packages rotatably mounted on the pintle in the container; an annular member, having a series of notches and a central opening forming a part of the magazine; a shaft journaled in the cover; an operating handle on the shaft exteriorly of the case; a centering plate on the shaft formed to enter the central opening of the magazine; and a gravity actuated dog pivotally mounted on the shaft for entering one of the notches of the member, said magazine being provided with a perforated wall adapted to permit flow of water therethrough and to retain cracked ice therein.
3. In a package cooler and dispenser of the character described, an insulated case provided with a displaceable cover; a container removably fitted into said case having a peripheral turned flange at its upper edge; a magazine for the packages having a spider on its upper end provided with a notch; means for rotatably mounting the magazine in said container; a dog carried by said cover and engageable with the notch of said magazine when the cover is closed; and means operably connected with said dog and projecting above said cover for effecting rotation of the magazine in said container.

JEAN ROBERT BURDETTE.
